UNITED STATES PATENT OFFICE.

WILLIAM P. DIETZ, OF BALTIMORE, MARYLAND.

PLAYING CARDS.

Application filed November 24, 1922. Serial No. 603,087.

To all whom it may concern:

Be it known that I, WILLIAM P. DIETZ, a citizen of the United States, residing at Baltimore, Maryland, have invented certain new and useful Improvements in Playing Cards, of which the following is a specification.

This invention relates to a novel deck of playing cards by the use of which various games may be played in simulation of an election contest, and one of the primary objects of the present invention is to provide a deck of playing cards in the use of which a greater variety of combinations are rendered possible than in the use of ordinary playing cards.

Another important object of the invention is to provide a deck of playing cards in which the relative values of the cards 20 may be selectively and arbitrarily determined according to color, symbols, emblems, and numerical designations.

In the accompanying drawings:

Figures 1 to 16, inclusive, are plan views 25 illustrating the cards comprising a suit of one color;

Figures 17 to 20, inclusive, are similar views illustrating the emblem cards of a suit of another color;

Figures 21 to 24, inclusive, are similar 30 views illustrating emblem cards comprising a set independent of the several main color suits, and

Figures 25 to 28, inclusive, are similar 35 views illustrating emblem cards of a suit of still another color.

The invention contemplates a deck comprising fifty-two cards which may be divided into three main suits of distinguishing 40 colors and each embracing a total of sixteen cards, and an independent suit of another distinguishing color embracing a total of four cards. Figures 1 to 16, inclusive, in the drawings, illustrate all of the cards comprising a suit of one color as, for example, blue, and the cards comprising the two other main suits will be printed in distinguishing colors, for example, gold and red. Each main suit comprises four emblem cards and 45 twelve cards having designated numerical value. Figures 1 to 4, inclusive, illustrate the four emblem cards of the blue suit, these cards being indicated in general by the numerals 1, 2, 3 and 4. Each card bears upon 50 its face, in diagonally opposite corners, a symbol, such, for example, as a letter of the

alphabet representing the initial letter of the name of a political party, as indicated in each instance by the numeral 5. For example, the card 1 will bear the letter "I" 60 representing the initial letter of the "Independent" party; the card 2 will bear the letter "B" representing the initial of a "Bloc" party; the card 3 will bear the letter "D" representing the initial of the "Democratic" party; and, the card 4 will bear the letter "R" representing the initial of the "Republican" party. Likewise each of these cards may bear upon its face in the other diagonally opposite corners, a symbol in the 70 distinctive color of the suit and indicated by the numeral 6, and this symbol may, for example, be in the nature of a representation of a cross mark and may be symbolic of the cross mark placed on a ballot by a voter. 75 Each of the cards 1, 2, 3 and 4 will also preferably have printed upon its face one or more representations of the emblem of the particular party which it represents, and in the illustrated embodiment of the invention, the card 1, representing the "Independent" party may bear as an emblem, the representation of a goat; the card 2 may bear the representation of a pig, emblematical of a "Bloc" party; the card 3 may bear 85 the representation of a donkey, emblematical of the "Democratic" party; and, the card 4 may bear the representation of an elephant, emblematical of the "Republican" party. These emblematical images, in each instance, 90 are indicated by the numeral 7. Each of the cards 1, 2, 3 and 4 also has printed upon it, as, for example, at each end, a legend, indicated by the numeral 8, which may, for example, be indicative of the principles or interests of an aspirant to office or the party 95 which he represents.

The numerical cards of the suit are illustrated in Figures 5 to 16, inclusive, and are indicated in general by the numeral 9, each 100 card bearing upon its face at diagonally opposite corners, symbols 10 corresponding to the symbols 6 of the emblem cards, and in the other diagonally opposite corners bearing ordinals indicated by the numeral 105 11 and representing the numerical values of the respective cards. Each card 9 also bears upon its face, in the space occupied by the emblems 7 upon the cards 1, 2, 3, and 4, one or more ordinals 12 preferably of large 110 and readily discernible size and corresponding to the ordinals which are indicated by

the numeral 11. Also each card 9 will bear upon its face legends 13 corresponding in character to the legends 8 previously referred to in connection with the emblem 5 cards, and by comparison of the several figures representing the numerical cards, it will be observed that the nature of the aspirant's interests or purposes, in seeking office, is more or less in consonance with the numerical 10 values of the cards.

If desired all of the devices printed upon the face of each card of the suit may be represented in solid color or in outline, or only one of the various devices may be represented in color as, for example, the symbolic devices 6 and 10 of the emblem and numerical 15 cards, respectively.

Figures 17 to 20, inclusive, correspond to Figures 1 to 4, inclusive, and illustrate the emblem cards of another one of the suits as, for example, that one of gold color. Similarly, Figures 25 to 28, inclusive, illustrate the emblem cards of the third main suit and are printed in a distinguishing color such, 20 for example, as red.

Figures 21 to 24, inclusive, illustrate the cards comprising an independent suit, and these cards are indicated by the numerals 14, 15, 16 and 17. These cards bear initial 25 letters 18 corresponding to the letters 5 heretofore referred to, and they also bear emblems 19 representative of the political parties, of the names of which the letters 18 are the initials. Also a symbolic character 30 or device, indicated by the numeral 20, is printed upon the face of each of the cards 14, 15, 16 and 17 preferably in the same position as the devices 6 and 10 heretofore referred to. This symbolic device or figure is, 35 however, preferably different from the said devices 6 and 10, and may, for example, resemble what may be termed a double cross. The cards 14, 15, 16 and 17 are preferably 40 printed in black. The cards 14, 15, 16 and 17 also bear legends 21 corresponding to the legends 8 and 13 and of a character indicating inferior morals.

From the foregoing description it will be 45 evident that there are three main suits, each represented by sixteen cards of a distinguishing color, and an independent suit of some other color such, for example, as black, and which latter suit comprises only four 50 cards which, as previously stated, are represented in Figures 21 to 24, inclusive. The distinguishing colors of the several suits 55 may be given preference in a predetermined ranking order. For example, the cards of the gold suit may be considered to rank highest, and the cards of the blue, red and black suits of less value in the order named, 60 although this is purely an arbitrary selection of colors. In any event the cards of the black or independent suit which are only 65 four in number, will be deemed of inferior

value in accordance with the character of the legends 21 borne thereby, and various arbitrary rules may be adopted relative to the value of these particular cards and the advantages or disadvantages to be gained 70 or incurred by holding them in the playing of a game. The legends, numerals and colors are divided equally among the four political parties and the numerical cards represent voters, each of said cards having 75 a voting or scoring value determined, preferably, by the numeral appearing on the card. The playing value of the cards is determined by their numerals, the emblem cards having the highest playing value, and, 80 in the event of a tie in the value of the sets of cards, the colors of the cards will determine the value, as above stated. The cards are dealt one at a time and the players deal 85 in turns as in other games. One color may be selected as "trump" and will then be more valuable than any other color but, if there be no "trump" the colors retain their original relative values. The black or double cross cards may be used in many 90 ways, as jokers, bowers, or penalty cards.

As players become familiar with the cards, various rules will be formulated and games developed. I have formulated rules 95 for a game which I call "General election" in which the object is to bid for and secure as many votes as possible. The total votes of the game may be any number decided upon by the players. The object of the bid is to claim as many votes as a player 100 may think he can capture, either alone or with the help of a partner. The cards are shuffled and dealt equally, if possible, but, if the number of players in the game is such that an equal distribution is not possible, 105 the cards remaining after the deal are placed in the discard. Each player, in turn, selects a political party and mentions the name of that party and the amount of his bid, the highest bid winning and the player making such bid beginning the play. The player will lay in the center of the table one 110 of his party emblem cards and call for the numerical cards bearing the same legend as that appearing upon his played party emblem card. Each player, in turn, must play one card, if possible the card called for. All cards played which are not called for 115 must be placed in the discard unless they are claimed by a player who has the corresponding legend emblem card which he has used as a call card and is exposed in front of him. Each player, in turn, leads a call card and leaves the same and the corresponding legend card in front of him face up. The 120 value of a trick is determined by computing the values of the cards played to it and belongs to the leader. If a player cannot play a card called for, he may, of course, play any card from his hand and if he should 125 130

play a double cross emblem card of the leader's party it will count five votes against the leader. The "new vote" cards, which are shown in Figs. 5 and 6, will be claimed and counted by the leader of a trick in which said cards are played. The cards may be given arbitrary counting value and after one hand of each player has been played, the counting or voting value of the several cards are added and the player having the highest total is declared the winner, although it is permissible to play until some one player has reached the predetermined grand total in order to be decided the winner. Any player failing to secure the number of votes for which he bid will lose the whole amount of his bid.

Having thus described the invention, what is claimed as new is:

- 20 1. A deck of playing cards embodying a plurality of suits each having a distinctive color and embracing a series of cards emblematic of political parties and a series of cards representing voters and carrying numerical designations, and an independent suit embracing only a series of cards emblematic of political parties.
- 25 2. A deck of playing cards embodying a plurality of suits each including a series of cards bearing emblems indicative of politi-

cal parties and a voting symbol and a series of cards having numerical designations and the same voting symbol, and an independent suit including only a series of cards bearing emblems indicative of political parties, and 35 a voting symbol different from the voting symbol upon the cards of the first-mentioned suits, each suit having a distinctive color.

3. A deck of playing cards embodying a plurality of suits, each including a series of emblem cards representing political parties and a series of numerical cards, all the cards of said suits having the same voting symbol thereon, and an independent suit including 45 only a series of emblem cards representing political parties, the cards of the independent suit having thereon a voting symbol different from the voting symbol on the cards of the first-mentioned suits, each suit having 50 a distinctive color, the several emblem cards each having a legend thereon expressive of ambitions or intentions of political candidates and like legends being placed on the numerical cards, the colors, numerals and legends being divided equally among the political parties. 55

In testimony whereof I affix my signature.

WILLIAM P. DIETZ. [L.S.]
